CLAIM

The ornamental design for an apparatus for rehabilitation, as shown and described.

DESCRIPTION

FIG. 1 is a top, front left perspective view of an apparatus for rehabilitation showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom, front left perspective view thereof; and,

FIG. 9 is a top, front left perspective view showing use state thereof.

The broken lines in FIG. 9 are for illustrative purposes only and form no part of the claimed design.

The broken lines in FIG. 3 represent portions of the apparatus for rehabilitation that form no part of the claimed design.

1 Claim, 9 Drawing Sheets
